UNITED STATES PATENT OFFICE.

SAMUEL MUELLER, OF JERSEY CITY, NEW JERSEY.

DESIGN FOR NOODLE OR MACARONI.

42,608.

Specification for Design.

Patented June 11, 1912.

Application filed May 15, 1909. Serial No. 496,330. Term of patent 14 years.

To all whom it may concern:

Be it known that I, SAMUEL MUELLER, a citizen of the United States, residing at Jersey City, Hudson county, in the State of New Jersey, have invented a new, original, and ornamental Design for Noodles or Macaroni, of which the following is a specification, reference being had to the accompanying drawing, forming part thereof, in which—

Figure 1 is top view of a noodle or macaroni incorporating my said design; Fig. 2 is a side view thereof, and Fig. 3 is an end view.

In said drawings the noodle or macaroni

as shown consists of a narrow longitudinal body folded about midway of its ends to form two diverging members which are again folded intermediate their ends and the fold first named to form laterally projecting ends arranged at acute angles to said diverging members.

I claim—

The ornamental design for a noodle, as shown and described.

SAMUEL MUELLER.
